UNITED STATES PATENT OFFICE

BION C. PLACE, OF DETROIT, MICHIGAN, ASSIGNOR OF ONE-HALF TO GEORGE E. GAGNIER,
OF DETROIT, MICHIGAN

WALL INSERT

Application filed July 10, 1931. Serial No. 549,981.

This invention relates to wall inserts designed to provide for the ready attachment of door frames, window frames, moldings or the like to concrete or similar initially plastic walls, and at the same time to provide means for housing electrical conduits or the like.

In modern building construction involving the use of concrete or similar initially plastic material in the construction of the walls, provision is usually made for the attachment of molding and finishing frames to the walls. Generally wooden inserts are placed in the molded wall in position to receive the driven fasteners that secure the moldings or finish frames to the wall after completion thereof. Such arrangements are not entirely satisfactory and they are relatively costly in installation.

Moldings and finishing frames and the like can be satisfactorily attached to walls by means of spring or such fasteners, if the walls are provided with inserts designed to receive such fasteners. A satisfactory spring fastener for this purpose that requires only an opening in a sheet of metal to constitute a satisfactory socket for the insertion of the resilient shank of the fastener is disclosed in my Patent No. 1,679,266, granted July 31, 1928.

This invention aims to provide an insert for concrete or similar initially plastic walls that will provide the necessary openings when it has been inserted in a wall to enable fasteners of the kind described in the patent just referred to, or equivalent fasteners, to be used in attaching moldings, trim frame members or the like to such walls.

Another object of the invention is to provide a metal insert for a wall that is designed to provide a means to hold the insert embedded in the wall, and that is so shaped that the insert may be used with equal facility in a floor, ceiling or wall, as well as in a corner between a floor and wall, or between two walls disposed at right angles to each other.

Another object of the invention is to provide the wall insert that is normally of hollow form open only at each end so that the insert can be embedded in the walls, while the interior thereof is maintained free of the ini-

tially plastic material of which the wall is composed, which insert at the same time is designed so that openings may subsequently be provided therein in an extremely simple and effective manner by using tools that are readily available.

A still further object of the invention is to provide a wall insert that may be used to provide a socket, or sockets, for spring fasteners that may be applied to moldings or trim material for walls, that is so constructed as to provide at the same time a convenient housing for the reception of electrical conduits or the like, and that is especially equipped so as to enable an opening to be made in a wall of the housing by simply completely removing a portion of said side which is substantially completely severed from the remainder of said side during the manufacture of the insert.

Still further objects of the invention will appear as a description thereof proceeds with respect to the accompanying drawing in which

Figure 1 is a fragmentary view of a portion of the wall having a section of an insert corresponding to the present invention embedded therein.

Figure 2 is a vertical section of the wall and insert strip illustrated in Figure 1, a molding and spring fastener being shown in position in dotted lines, illustrating one mode of using the insert constituting an essential part of the present invention.

Figure 3 is a longitudinal section on the plane indicated by the line 3-3 in Figure 1, the partially separated metal that normally covers one of the openings in the strip being bent out of the plane of the side of the insert to illustrate a mode of opening the holes in the insert.

Figure 4 is a fragmentary sectional view showing another use of the insert of this invention and one way of using such insert when put to such use.

Figure 5 is an elevational view showing a modified form of insert strip designed particularly for the purpose of receiving electrical conduits.

Figure 6 is a sectional view taken on the 100

plane indicated by the line 6—6 in Figure 5.

Figure 7 is a sectional view showing an other mode of using the insert strip of the present invention.

5 Like reference characters indicate like parts throughout the several figures.

The insert strip of the present invention is preferably constructed of sheet metal. A blank of elongated form and proper width 10 is first provided with a multiplicity of slits at the points along the length thereof at which openings may be required in the completed insert. The slits may be made in any convenient substantially closed form, though 15 a small portion, or portions, of the metal necessary to complete the enclosed form is unsevered or uncut so that the metal almost separated by the slit is maintained in position to close the openings that is formed 20 when said small portion, or portions, are subsequently cut.

If the openings are to be round in outline, as is preferred if such openings are to be used to receive the resilient shanks of snap 25 or spring fasteners, the slits are made in a substantially completely circular form as illustrated by the numeral 10, small portions necessary to completely separate the portion of the blank between the lines of the substantially complete slit 10, designated by 11, are maintained unsevered. The slits 10 are formed at intervals along the length of the blank, the partially severed metal between 30 the substantially closed slits 10 being held in position in the plane of the metal in which 35 said slits are formed by the unsevered portions 11.

After the blank has been provided with 40 the slits just described, it is bent into the form of a hollow housing. Preferably, the housing is formed so that it is triangular in cross-section. As illustrated in the drawing, the mid-portion of the metal 12 in which 45 the slits are formed, constitutes a side of the insert that is to be exposed. The portions of the blank adjacent the mid-portions 12 are turned inwardly and converge toward each other, said convergently disposed sides 50 being designated by the numerals 13 and 14. The portions 13 and 14 are arranged so that a right angle is formed between them. To this end portions 13 and 14 preferably are each bent at a 45° angle to the exposed 55 side 12 of the insert, though other equivalent arrangements may be employed. The portions 13 and 14 converge toward a point of complete convergence 15 from which the edges 16 and 17, constituting respectively 60 the margins of the portions 13 and 14, flare outwardly or are turned away from each other from said point 15. Preferably, the hollow housing thus provided is maintained permanently in the described form by welding 65 or otherwise rigidly attaching the por-

tions 13 and 14 together at the point of convergence 15.

The insert thus formed may be put to a number of uses. It may be embedded in a vertically extending wall 18 by disposing the insert so that the side 12 thereof will be exposed when the wall is completed. The wall is then molded around said strip, the outwardly flaring portions 16 and 17 firmly and positively holding the insert in position after the wall has been completed. The initially plastic material of which the wall is composed cannot enter the housing defined by the sides 12 and the portions 13 and 14 of the insert, since the metal substantially completely severed by the substantially completely closed slits 10 is maintained in position closing the openings that would result upon the removal of the metal virtually completely separated from the side 12.

When the insert has been positioned in the wall in the manner just described, it is admirably adapted to enable the trim material, such as the window and door frames or molding ordinarily used to finish the interiors of rooms, to be readily attached thereto by means of my spring fasteners. To this end the inserts are positioned in the wall so that they may serve the specific purpose for which they are intended. They may extend vertically, horizontally, or diagonally in the wall, ceiling or floor in accordance with the need for the use to which the insert is put.

In Figure 2 the insert is shown, by way of example, as a means for attaching a molding, such as a picture molding, the molding and the preferred spring fastener being indicated in dotted lines in said figure. When it is desired to attach said molding, the openings are provided in the insert by either breaking away the small disks of metal substantially separated from the sides 12 or the slits 10, or by bending said disks inwardly as shown at 19, Figure 3. Either of these operations may be accomplished by the ordinary use of tools that are immediately available, such as a punch or nail set, for example.

The molding may assume any desired form such as that illustrated in Figure 2 showing a sheet metal molding having an ornamental base portion 20 formed from the mid-portion of a sheet metal blank, a portion 21 and two inwardly extending flanges 22 and 23 disposed in the same plane with a gap between them. The spring fasteners are inserted so that the shank 24 thereof extends through said gap and so that the head 25 thereof laps the adjacent inwardly turned flanges 22 and 23. The molding is positioned by causing the resilient shank 24 to enter the opening, the engagement of the shanks 25' and 26 with the edges of the openings causing a contraction of the shank of the fastener that enables it to be passed through said opening. As the movement of the fastener through the

opening is continued, the shank expands and the convergently disposed holding portions 27 and 28 serve to hold the molding in position with a firm yielding action. Door 5 frame or window frame strips may be applied in the same manner.

The insert just described is, by virtue of its form, inherently capable of being set into a wall or disposed across a corner between 10 adjacent walls, or between a wall and the floor or the ceiling. When it is desired to locate the insert in a corner, as just stated, it is applied to the corner in the manner indicated in Figure 4 of the drawing, so that the 15 portions 13 and 14 are located in abutment with the adjacent walls, the outwardly flaring portions 16 and 17 being embedded in the initially plastic material immediately adjacent the corner in which the insert is positioned as clearly shown in this figure.

When put to this use the insert may serve a number of purposes, as for example the securing of a rug 29. When used for this purpose, the openings are formed in the insert 25 after it has been completely installed in the manner above stated. The rug may be secured by providing the edges thereof with openings 30 approximately opposite the openings in the insert. Short sheet metal 30 clips or holding members 31 provided with openings for the reception of the shank 32 of the snap fastener of the type above referred to are disposed with the openings approximately in alignment with the openings 35 30 in the rug and the opening in the insert. The fastener is then inserted in the manner above described through the aligned apertures, until the head 33 bears firmly against the holding element 31 securing said holding 40 element and the edge of the rug to the insert. The holding element 31 is preferably provided with outwardly bent tongues 34 and 35 for the reception of a finish molding 36 having inwardly turned edges 37 and 38 45 that are sprung behind the tongues 34 and 35, respectively. Any other arrangement for securing the rug utilizing the insert placed as just described may be employed. The insert when used in the corner may likewise be used for many other purposes than 50 for securing rugs.

The insert of the present invention may likewise be used to serve the further function of housing the electrical conductors that are 55 ordinarily used to wire buildings for lighting and other purposes. When put to such use the insert may be formed as illustrated in Figures 5 and 6, in which 12' designates the normally exposed side of the insert. Said 60 side is provided with a slit 39 of relatively large rectangular or similar closed outline. The slit 39 substantially serves a relatively large portion of the side 12' of the insertion, small portions such as 40 and 41 being maintained unsevered prior to the embedding of

the insert in the wall with the portions 13' and 14' and the flaring portions 16' and 17' arranged as before. A plurality of electrical conductors 42 are disposed in one of the angles of the insert which constitutes a housing for 70 said conductors in this instance. After the installation of the conductors has been completed and it is desired to provide the necessary outlet, the opening in the side 12' may be provided by severing the portions 40 and 75 41 or by bending the metal covering the opening inwardly so that outlet connections of any approved form may be made with the conductors 42. The same strip may be provided with openings 10' for the reception 80 of spring fasteners so that finish moldings or the like may be carried up to the outlet formed as just described. Or said strip may be provided with suitable further openings disposed so as to provide for the attachment 85 by spring fasteners of switch cover plates for said outlet.

The insert strip of this invention may also be used with facility in brick or tile walls that are subsequently plastered. A preferred way of employing such strip is shown in Figure 7, in which 43 indicates two layers of bricks or tiles of a wall. Said layers are separated from each other by a mortar 44 following conventional practices. The outwardly flaring portions 16 and 17 of the insert strip are embedded in mortar 44, said strip being positioned in the mortar so that the face 12 of the strip projects outwardly 90 from the brick or tile wall an amount equal to the thickness of the plaster 45 subsequently applied thereto in well known manner. The plaster adjacent the strip is interlocked in back of the inclined walls 13 and 14 of the strip so that a satisfactory joint results 95 along both edges of the strip. The face 12 is provided with slits that enable openings 100 to be later readily formed therein as above described.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:—

1. An insert strip for initially plastic walls, comprising a hollow body, provided with means designed to hold the body to the 125 wall when embedded therein, said body including an exposed side provided with a cut substantially completely, but not entirely, severing a portion of said side from the remainder so that an opening may be readily 130

formed through said side by removing said portion.

2. An insert strip for initially plastic walls, comprising a hollow body, provided with means designed to hold the body to the wall when embedded therein, said body including an exposed side provided with a multiplicity of cuts each substantially completely but not entirely severing a portion of said side from the remainder so that one or more openings into said body may be readily provided through said side by removing one or more of said portions.

3. A sheet metal wall insert strip, comprising a hollow body having means to hold said body in a wall in which it may be embedded, and including a substantially complete opening in said body formed by severing a portion of a sheet metal face without completely separating said portion which is maintained in said opening so as to close the same and still be readily separable when it is desired to provide a complete opening in said body.

4. A sheet metal wall insert strip, comprising a hollow body having means to hold said body in a wall in which it may be embedded, and including a side arranged to be exposed, said side being provided with a multiplicity of slits of approximately closed form, whereby openings may be readily formed in said insert after it has been fixed in a wall.

5. The insert strip of claim 4 constructed by bending the mid-portion of a sheet metal blank into triangular form and integrally uniting the edges of said portion at an angle of the triangle.

6. A wall insert strip having a hollow cross-sectional form including three straight sides, the angle between two of said sides being substantially 90° whereby said strip may be used in corners and means projecting away from said form designed to hold said form anchored to a wall when said means are embedded therein.

7. A wall insert strip having a hollow cross-sectional form including three straight sides formed by bending an elongated strip of metal into triangular form, one of the angles of the triangle being a right angle and means projecting away from said form designed to hold said form anchored to a wall when said means are embedded therein.

8. A wall insert strip formed from an elongated sheet metal blank, the body of which is bent into triangular form and the edges of which flare outwardly away from each other, one of the angles of the triangle being a right angle and means in the wall of the triangular form opposite said right angle permitting fasteners to be interlocked therewith.

9. A hollow wall insert strip comprising a side designed to be exposed when the strip

is positioned in a wall, and two further sides converging toward each other and forming a right angle between them, each of said converging sides being extended beyond the point of convergence and being flared outwardly to provide means to hold the strip embedded in said wall.

10. The strip defined in claim 9 in which said side designed to be exposed is provided with a plurality of slits in the form of a nearly closed figure to enable openings to be readily formed in said side.

11. A wall having a hollow elongated metal insert strip embedded therein when the wall is in plastic condition, said strip being triangular in cross section and having a portion projecting beyond the wall, one side of the triangular cross section being arranged parallel to said wall, and a plaster coating for said walls interlocked behind the other two converging sides of the triangle formed by the sides of the strip.

In testimony whereof I affix my signature.
